APPARATUS FOR FORMING AND IMPREGNATING FIBROUS PADS

Crosby Field, Brooklyn, and Gerald C. Toole, St. Albans, N. Y., assignors to Brillo Manufacturing Company, Inc., a corporation of New York

Original application December 27, 1938, Serial No. 247,762, now Patent No. 2,240,135, dated April 29, 1941. Divided and this application August 2, 1940, Serial No. 349,730

37 Claims. (Cl. 29—1)

The present invention is herein disclosed as applied to specific cases where the materials and apparatus are primarily designed for making steel wool pads, and for impregnating them with soap; but various features of the method, and also of the apparatus, may be useful as applied to specifically different materials, or purposes.

Certain methods disclosed herein are claimed in our prior application, Ser. No. 247,762, filed December 27, 1938, now Patent No. 2,240,135, granted April 29, 1941, of which this apparatus application is a division.

Specifically considered, this apparatus includes means for making the pads from metal wool, usually steel wool, preferably in the form of a continuous strip comprising a large number of long, curly, springy fibers. Steel wool fibers as blown off from a predetermined number of adjacent knives of wool cutting machines of the type disclosed in Field Patent No. 1,608,481, readily form fluffy springy strips suitable for our purposes. Under normal conditions or under predetermined applied tension, equal lengths of such strip will contain the same amount of wool.

According to the present invention, feed mechanism pulls the strip material into the machine intermittently, each pull measuring off the same length of strip, each strip containing sufficient wool for one pad.

Each length is cut off by a suitably timed knife, and the feed mechanism pushes the leading end of the strip into a forming chamber, and then completely releases it. The cross-section of this forming chamber is preferably the same as the larger-area dimensions of the pad.

After the leading end of the strip has been pushed into said chamber, opposite, continuously-rotating spinning needles, are forced into said leading end. These needles are axially aligned and rotate in planes parallel with the direction of the feed-in, so that the untensioned, leading and trailing portions of the fluffy strip, are wound in a few fluffy layers, the volume of which may be several times the volume of the pad to be made therefrom.

On each spinner there are preferably two needles, located eccentrically to their axis of rotation, so that the interior of the pad consists mostly of the leading end of the strip; and, the exterior layers as wound on the outside of said needles, tend toward elliptical; but when the needles are withdrawn, the outer layers become more cylindrical. This cylindrical structure and its fluffiness are important as concerns uniformity of distribution of the wool, when the rela-

tively large diameter cylinder is flattened to form a relatively thin pad.

While the above features are important merely as concerns making standard-size pads, an important feature includes discharging a measured amount of soap of predetermined fluid temperature upon said fluffy cylindrical mass of the metal wool; preferably downward, so that distribution of the fluid soap in the fluffy mass, is assisted by gravity.

The chamber in which the fluffy cylinder of wool is formed and impregnated, is preferably the interior of a compressor, the bottom of the chamber being the compressing piston, and the top being the pad-shaping mold into which the relatively voluminous mass is compressed by the piston. Preferably the top or end-closing wall of this mold is formed with passages through which the fluid soap is ejected downward into the cylindrical mass, just after the upmoving piston has closed the lateral inlet, but before it has applied any substantial compression. These passages are preferably of relatively small cross-section and are distributed over a considerable area of the top end of the mold, so as to properly distribute the soap. As explained below, distribution of the soap may be assisted by beginning its discharge before friction, or compression, has completely stopped rotation of the cylindrical wool; and, in any event, the high pressure applied in flattening the pad is highly effective for distribution of the soap throughout the thickness of the pad.

This upper end wall of the mold could be made removable, and the piston given an additional vertical movement for ejecting the pad, but there are special advantages in making this end wall a stationary plate, permanently connected with, and forming the bottom of the soap supplying chamber. This requires making the side walls of the mold, slidably edgewise, into and out of registry with the compressor. In the form of apparatus shown such edgewise movement of the mold frame is effectively provided for by having a series of mold frame holes formed in a rotary plate which is mounted on an axis parallel with the compressor, and provided with indexing mechanism whereby successive mold frame holes may be moved into operative registry with the compressor to receive and shape a pad, and then carry it to a position in registry with an ejector, whereby the formed pad is ejected from the frame, preferably downward, so that the pad falls on a conveyor which carries it to a point suitable

for other operations, as for instance drying, cooling or packaging the pads.

The above and other features of our apparatus, as well as of our method, will be more clearly understood from the following description in connection with the accompanying drawings, in which

Fig. 1 is a top plan view;

Fig. 2 is a vertical section on the line 2—2, Fig. 1;

Fig. 3 is an end elevation viewed from the left of Figs. 1 and 2;

Fig. 4 is a detail plan view of the mold frame rotor and a Geneva cam drive and stop mechanism in operative relation thereto;

Figs. 5 and 6 are detail views on a large scale, showing the strip-gripping feed-in mechanism, in its relation to the knife for cutting off the rear end of the tensioned and measured strip of metal wool; Fig. 5 being a plan view; and Fig. 6 being a front end view of the parts as shown in Fig. 5;

Fig. 7 is a vertical section on the line 7—7, Fig. 2, showing the compressor, spinning needles, operating mechanism therefor and the soap supplying means at the upper end thereof;

Fig. 7a is a detail perspective showing the cams and levers for actuating the valve and piston of the soap pump;

Fig. 8 is a plan view showing the cams and driving mechanism for controlling simultaneous inward and outward movements of the continuously spinning needles; and

Fig. 9 is a perspective view of a square soap and metal wool pad which will be formed when the cross-sectional shape of the compressor chamber and mold is a square.

Referring to these drawings, it will be seen that while various of the above described steps of our method could be performed by hand, and some of them could be omitted, a very important part of the invention is the apparatus, which is a complete machine organized so that all of the steps are automatically formed, in proper succession on each pad; and some of the operations are being simultaneously performed on successive pads.

Referring to Fig. 2, supplemented by Figs. 1 and 3, it will be seen that the fluffy longitudinally elastic strip material x enters the machine through a rectangular funnel 1, in alignment with a pair of idler rolls 2, one of which is vertically adjustable by screws 3.

As shown in Fig. 2, the leading end of the ribbon x^1 is in the plane of the rotary knife 4, and rests on stationary shear 4a. See Figs. 5 and 6.

Traction on the ribbon is applied by two spaced sets of six each of fingers 5, 5a, the fingers of one set 5 being attached crosswise to, and projecting laterally from, two sets of parallel chains 6, 6, which are similar, and are supported and caused to rotate at the same speed by three pairs of sprockets, namely, sprockets 7, 7, on shaft 7a at the feed-in end; 8, 8, on shaft 8a at the delivery end of the feed; and 9, 9, intermediate. The latter are on separate shafts 9a, 9a, which are each vertically adjustable, as by shims, for the purpose of taking up slack. The fingers of the cooperating set of fingers 5a, are carried by precisely similar, symmetrically opposite pairs of chains, and sprockets, on shafts 1a, 1a, and 9a respectively.

As shown more clearly in Fig. 3, the sprocket shafts 1a, 1a are caused to rotate equally and oppositely by 1 to 1 gears 1b, 1b. Shaft 1a is driven through sprockets 1c, chain 1d, and sprock-

et 1e, on shaft e, Fig. 2; and shaft 1a is driven from 1a, through said gears 1b. All the other feed chain sprockets are idlers, driven through said feed chains.

Each set of fingers 5, 5a, consists of several fingers in series, and preferably the laterally-projecting wool-engaging portions of these fingers are each covered by rubber tube as 5b, Figs. 5 and 6. As will be obvious, the chains cause these fingers to travel in the direction of the arrows Fig. 2. They successively engage the ribbon x^1 , in the rear of its leading end and pull it endwise between upper and lower plates 10, 10a, of an open ended, box-like passage; and then push said leading end through opening 11 in the side of a vertical compressor chamber 12. The opposite fingers separate successively, the last pair leaving the ribbon entirely free. In a special case, with 6-tooth sprockets, half inch links, fingers on 6 links, and with the initial finger-engagement an inch or so in rear of the leading end, about 2½ inches of the ribbon may be pushed into a 2¾ inch compressor chamber.

Before this happens, however, and while the ribbon is still being pulled through passage 10, 10a, against tensioning resistance of idler rolls 2, the knife 4 cuts off the measured length of tensioned ribbon, x^2 (Fig. 1), thereby freeing it from tension. This knife is rigidly mounted on rotating shaft 4b, and its rotation is timed so that it passes the stationary shear 4a when the proper length shall have been measured off; thus leaving a leading end of ribbon x^1 resting on said stationary shear, as described above.

The bottom of the chamber 12, is the retracted compressor piston 13, and the top is the stationary plate 15, against which the piston compresses the metal wool to form the pad.

The piston is in the lowermost position while the sets of fingers have been pushing the leading end of the ribbon into the compressor and have released the ribbon, leaving it entirely free. While the piston is still in this lowermost position (see Figure 7), pairs of rapidly spinning needles 17, 17a, are projected endwise into the box and into engagement with the leading end of the ribbon therein. These needles are eccentrically located with respect to the axes of shafts 29, 29a, by which they are rotated. Being rapidly revolved in planes parallel with the length of the ribbon (Figure 2), and the cut-off length of ribbon being free, the needles quickly wind it up into cylindrical form. Thereupon the needles are withdrawn, leaving the loosely rolled cylinder of metal wool free, within the compressor chamber.

The lateral stresses applied on the needles in winding the free ribbon are very small, and means for giving them their endwise and rotary movements may be correspondingly simple. As shown in Fig. 7, the needles are similarly and symmetrically arranged, as also the means for giving each pair the required movements. The needles 17 are endwise slidable in a rotary bushing or journal 18, which is rotatably mounted in the wall of the compressor chamber, with their inner end walls flush with the inner surface of the chamber. Needles 17 are rigidly secured in a disc 19 which is secured to and rotated by a shaft 29. Said shaft is rotatable in a slidable block 21, which is keyed against rotation by slidable engagement with a parallel stationary guide-bar 22. The non-rotating slidable block 21, imparts forward movement (toward the center of chamber 12) to the spinner by pushing against disc 19; and retracting movement by pushing against

a collar 19a which is secured on shaft 20. Said shaft 20 is slidably splined in a bushing or journal 23, which is rotatably mounted in the frame of the machine as shown, and which is driven through sprocket 24 by chain 25.

An intermediate portion of chain 25 engages a sprocket on countershaft 26. This latter sprocket is of the same diameter as sprocket 24, consequently shaft 26 rotates at the same rate as needle shaft 20. At the other end of shaft 26, a similar sprocket drives chain 25a which drives a sprocket 24a precisely similar and symmetrical with respect to sprocket 24; and all the movements of the needles, 17a, with respect to this sprocket, and means permitting them, are the same, but symmetrically opposite to those for needles 17; except, of course, both sets of needles revolve in the same direction. Therefore, the means for projecting the pairs of needles endwise into the compressor chamber and withdrawing them therefrom will be specifically described in connection with needles 17. As shown (Fig. 7), the block 21 is connected by link 27, to lever 28, which is pivotally anchored at 29 and which has intermediate its length a roller 29a bearing on cam 30 which is rotated by sprocket 31 on stationary journal 32. The lever 28, is tensioned by spring 33 so that the needles 17 will be projected into the compressor by spring pressure upon block 21; and the cam 30, as shown in Fig. 8, is formed with symmetrically located cam depressions which permit the springs to thrust the needle into the position shown in Fig. 7. The cam 30 also has symmetrical concentric cam projections which hold the needles in the withdrawn position. The depressions extend through relatively short arcs, so the needles operate for relatively short periods. This is permissible because they rotate at high speed, on a free untensioned length of the fluffy wool.

Fig. 2 shows that chain 25 which drives the spinning needles, is itself driven through sprocket 26b on shaft 2, which is driven by chain 26d, which is driven from a sprocket on the shaft of a motor not shown, but which as noted below is preferably the same electric motor that drives the compressor and spinner-shifting mechanism.

The spinner-shifting cam 30 is synchronized with all other parts of the machine, the sprocket wheel 31 which rotates it being driven through chain 31a, sprocket 31b, shaft p, bevel gears o, n, shaft m, sprocket l, chain k and sprocket j which is keyed to central shaft i, carrying the cam which operates the compressor. Thus the in and out reciprocations of the needles are timed accurately with respect to the movements of the plunger. The depressions and projections of cam 30, being symmetrical, as shown in Fig. 8, only half a revolution of the cam is required to feed one in and out cycle of endwise movement of the spinning needle. Consequently, since all other gears between the compressor cam shaft and the sprocket 31 have a one to one ratio, the proper one to two ratio for the cam is provided for by making sprocket 31 twice the diameter of driving sprocket 31b.

The central cam shaft i, is driven through speed-reducing gearing, and as shown in dotted lines Fig. 2, this includes sprocket h, on said shaft i; chain g; sprocket f; shaft e; sprocket d; chain c; sprocket b; and shaft a, which latter is driven through sprocket a' preferably from another sprocket on the same motor shaft that drives adjacent chain 26d, of the needle-spinning mechanism.

It will be seen that during the time when the spinning needles have been operating, the compressor piston 13 has been held in its lowermost position by the concentric small radius portion of compressor cam 40, which is engaged by a roller 13a, carried by radius arm 13b, pivoted on shaft 13c, and which controls said piston 13, through link 13d which is adjustable for wear and tear and also for various compressions that may be desired for the pads.

By the time cam 40 has rotated far enough to have roller 13a traverse the concentric small radius part of its groove and before the outward slant to the large radius part begins, the spinning needles will have completed their work of rolling up the metal wool in cylindrical form and will have been withdrawn. Thereupon the cam groove forces the compressor piston upward, closing the ribbon inlet opening 11 through the side walls of the compression chamber 12. Then, before the loosely wound metal wool has been substantially compressed, the pump operates to expel fluid soap through the cavity 50 and openings 51, into the compression cylinder 12, downward onto said uncompressed wool. As shown in Fig. 7, the discharge of the soap is effected by means of a piston 61 reciprocating in pump cylinder 62. The flow of the soap to and from this pump cylinder is controlled by a three-way valve 63, which, during the suction stroke, communicates with the supply pipe 64, through which the soap flows from the soap kettle. In the position shown in Fig. 7, the pump is in communication with the down-flow outlet pipe 66, through which the soap flows into said chamber 50. This three-way valve 63 is controlled by lever 68. It will be obvious from the Fig. 7 that when this lever is rocked on its axis, toward the right, the pump will be in communication with the soap supply pipe and the downflow outlet through pipe 66, will be closed.

As shown in Fig. 3, the means for operating the pump plunger and valve include the central shaft i, which rotates shaft r at right angles thereto, through 1 to 1 bevel gears; and shaft r, through chain s, rotates a higher level shaft t, at the same speed. As shown in Fig. 7a, shaft t carries a peripheral push-cam 70, which positively pushes upward on horizontal lever 71 and link 72 (see Figure 3), thereby causing bell crank 73, pivoted at 74, to retract link 75 which is pivoted to collar 16, which is adjustably secured on the stem 65, of piston in soap pump 62. The lever 71 (see Figure 7a), is pulled downward by a parallel lever 71a, which is pushed downward by said cam 70, this motion being transmitted to lever 71 through a link 77, which can be lengthened or shortened, as by axial rotation of its shank portion, to screw it in or out of the end pieces whereby it is pivoted to said levers 71, 71a.

There may be, and usually is a certain amount of lost motion between up-push on lever 71 and down-push on lever 71a; and this lost motion is biased in favor of contact of lever 71, with cam 70, by tension spring 78 (Figure 3) which is stretched forward from link 75, to the frame of the machine. The length of stroke of the pump may be changed by shifting the upper pivot of link 72, in the slot 72a of bell crank 73.

The pump valve lever 68, is shifted to soap intake and soap discharge positions, by link 79, bell crank 80, and link 81, which is actuated through a pair of parallel levers 82a, 82b (see Figure 7a), connected by adjustable link 82c, and engaging cam 83 on shaft t.

While the soap valve 63 is open (see Figure 2), the compressor piston 13 continues its upward movement and compresses the cylindrical wool into a relatively thin layer by pressure against the stationary end closure 15 through which the soap is being discharged. This pressure serves to flatten the cylindrical wool to a relatively thin square pad impregnated with soap, as indicated more or less diagrammatically in Fig. 9. Piston 13 then withdraws, leaving the cake in the mold; and the soap valve closes.

The side-wall, or frame element of the mold in which the piston 13 leaves the cake, is a square hole 12a in an edgewise movable plate 12b and, in this case this plate is a rotor which is shown in Fig. 4 as having eight such holes, equally distributed at equal distances from the axis of shaft 12c, on which said rotor is mounted. As shown in Fig. 2, this shaft 12c is parallel with the compressor; and, as shown in Fig. 4, the mold holes 12a are successively indexed to and held in position of registry with the compressor, by a rotary Geneva cam and stop drive 89, of well known type, which is keyed on the above mentioned vertical shaft p, as indicated in Figs. 2 and 4.

The upper end of this same shaft p (Figure 2) carries a cam 90 for holding out of operation and permitting operation of an ejector 91 registering with one of the frame holes 12a of rotor 12b. The shape of this cam is shown in Fig. 1, which in connection with Fig. 2 will make it obvious that the ejector 91 is held in retracted position, with the spring 92 compressed, during most of the revolution of said vertical shaft p. To so hold it, the cam 90 applies thrust on bell crank 93 operating through link 94 to lift the stem of the ejector against gravity and against pressure of said spring; but at the proper time, when the frame rotor is locked by the Geneva stop, a depression in the cam allows the spring to operate and eject the pad onto conveyer 100. The intake end of this conveyer (Figure 1) is rotated through sprocket 99, chain 98, and sprocket 97, on the above described intermediate shaft r which is rotated by shaft i, through the 1 to 1 bevel gears.

This shaft r also drives the rotary knife 4 through sprocket u, chain v, and sprocket w, on the shaft 4b, whereon the rotary knife 4 is mounted. Shaft 4b has slight endwise play, and is thrust to the left by spring 4c so as to yieldably hold the rotary knife 4 in shearing relation to the stationary shear 4a.

There are certain details of functioning of the spinning needles which contribute to the production of a fluffy cylindrical roll; and to a distribution of the wool therein particularly adapting it for flattening and compression into pads having approximately standard weight and standard distribution of wool therein, as well as standard thickness and peripheral form. Referring to Fig. 7, it will be seen that the bushings 18, which are rotated by the slideable needles 17, 17a, have their inner end surfaces flush with the walls of compressor chamber 12. Moreover, these continuously rotated bushings have a diameter substantially equal to the width of said chamber. Consequently, when the wholly free ribbon x² is engaged by the needles, the edge portions of said ribbon bear against surfaces that are rotating therewith, and they will encounter no frictional resistance and will be subject to no endwise compression until the strip has been wound to a width approximately that of said chamber. Moreover, the ribbon, being entirely free, there is nothing to apply any radial inward

pressure, or any longitudinal tension on the ribbon such as could promote tight winding; or otherwise deprive it of its characteristic of relative fluffiness.

Moreover, after the needles are withdrawn the cylinder tends to have end support and rotate with said inner end surfaces of said bushings; and even while the compressor piston is pushing the cylinder upward a distance substantially equal to its own diameter, substantial portions of the end surfaces of said cylinder are in contact with said rotating, high-speed inner end faces of said bushings, and tend to be more or less rotated thereby. These factors combine to form a cylinder with definite end surfaces and also to rotate such cylinder on its axis. So, while it is practically impossible to observe just when the wool cylinder stops rotating, indirect evidence, such as the distribution of the soap in the wool, indicates that at the time when the inlet opening 11 closes and the discharge of the soap begins, the wool cylinder has substantial rotation about its own axis, thereby distributing soap over the cylindrical surface thereof.

It will be understood that while our apparatus is described herein in connection with the impregnation of soap into metal wool pads it is applicable to the impregnation of any liquid into a mass of any fibrous material.

We claim:

1. Apparatus for making fluffy metal wool into relatively dense pads containing soap, said apparatus including a compressor having an upright compression chamber, a piston reciprocated through the lower end thereof and a pad shaping mold at the upper end into which the piston compresses the wool, the end wall of said mold being a stationary plate designed for discharge downward therethrough of soap at fluid temperature; means for supplying the compressor with enough fluffy metal wool for a pad; means for ejecting said soap downward through said stationary end plate onto the wool while it remains in relatively fluffy condition; and means for actuating the piston to apply high pressure to force the thus soaped fluffy metal wool into the forming mold, to distribute the fluid soap therein and form a relatively dense pad of predetermined shape; the frame walls of said shaping mold being laterally slideable beneath said stationary end plate to permit removal of the pad from said frame walls.

2. Apparatus for making fluffy metal wool into relatively dense pads containing soap, said apparatus including a compressor having a piston reciprocated through one end thereof and a pad shaping mold at the other end into which the piston compresses the wool; means for supplying the compressor chamber with enough fluffy metal wool for a pad; means for ejecting soap at fluid temperature onto the wool in said chamber while the wool is in relatively fluffy condition; and means for actuating the piston to apply high pressure to force the thus soaped fluffy metal wool into the forming mold, to distribute the fluid soap in the wool and form a relatively dense pad of predetermined shape; said shaping mold being formed of relatively movable sections permitting removal of the pad therefrom.

3. Apparatus as specified in claim 2, and in which the fluffy wool is a ribbon of the class described, and the means for supplying it to the compressor includes compression rolls for exerting predetermined resistance to pull of the ribbon therethrough, a traction feed mechanism

adapted to pull a predetermined length of tensioned ribbon through said resistance rolls, means for severing a predetermined length of said tensioned ribbon sufficient for a pad, and means for placing said length of fluffy untensioned ribbon in said compressor.

4. Apparatus as specified in claim 2, and in which the fluffy wool is a ribbon of the class described, and the means for supplying it to the compressor includes compression rolls for exerting predetermined resistance to pull of the ribbon therethrough, a traction feed mechanism adapted to pull successive lengths of said ribbon through said resistance rolls, means for severing a predetermined length of said tensioned ribbon sufficient for a pad, and means for placing said length of ribbon in said compressor; said means including spinning needles and means for projecting them into the chamber so as to engage the leading end of said ribbon and wind it into fluffy cylindrical form.

5. Apparatus as specified in claim 2, and wherein the end wall of the mold is stationary and the soap is discharged through one or more openings therethrough; and the side wall element of the mold is a laterally movable frame member fitting slidably beneath said stationary end wall of the mold, and movable into and out of registry with the compressor.

6. Apparatus as specified in claim 2, and wherein the end wall of the mold is stationary and the soap is discharged through one or more openings therethrough; and the side wall element of the mold is a laterally movable frame member fitting slidably between said stationary end wall of the mold and the compressor chamber, and movable into and out of registry with the compressor, said frame member being formed as a hole located in a plate mounted on an axis parallel with the axis of the compressor and rotated by indexing mechanism, into and out of registry with the compressor chamber.

7. Apparatus as specified in claim 2, and wherein the end wall of the mold is stationary and the soap is discharged through one or more openings therethrough; and the side wall element of the mold is a laterally movable frame member fitting slidably between said stationary end wall of the mold and the compressor chamber, and movable into and out of registry with the compressor; said frame member being formed as one of a plurality of similar frames equidistant from the center of a rotor turning on an axis parallel with the axis of the compressor, and rotated into and out of registry with the compression chamber, by suitable indexing mechanism.

8. Apparatus for making soap-containing metal wool pads from fluffy metal wool ribbons, which includes resistance means and traction feeding means for successively stretching lengths of ribbon, each to approximately the same predetermined tension; means for cutting off successive substantially equal lengths thereof while under such tension and for releasing them from tension; a pad shaping compressor including a piston and compression chamber, said chamber having a lateral opening through which the leading end of a cut-off length of said ribbon is pushed endwise into the compression chamber, by the feeding means, while the piston is retracted; means for loosely winding each length of ribbon, to fluffy, cylindrical form, in said cylinder; means for discharging soap at fluid temperature upon the outer cylindrical surface there-

of; said compression chamber having a closed pad shaping mold, into which the thus soaped fluffy metal wool is highly compressed, to distribute the fluid soap therein and form a relatively dense pad of predetermined shape.

9. Apparatus as specified in claim 8, and in which the means for loosely winding the ribbon in the compressor includes a pair of spinning needles endwise slidable in a rotary bushing having the inner face forming a portion of the compression chamber; and means for sliding said spinning needles endwise into and out of engagement with the leading end of the ribbon while the piston is retracted, thereby winding it into fluffy cylindrical form.

10. A machine for making soap-containing metal wool pads from fluffy metal wool ribbon, comprising serially related means for severing the ribbon into successive lengths of approximately equal weight; a piston and a compression chamber having a pad shaping mold into which the piston compresses the wool, and a lateral opening uncovered when the piston is in the retracted position; means for pushing a predetermined length of the leading end of said ribbon through said opening when the piston is retracted; spinning needles and means for projecting them laterally into said leading end of the ribbon and winding it to a cylindrical form; means for discharging soap at fluid temperature upon the outer surface thereof; and means for driving said mechanism to operate on the ribbon in cooperative synchronized succession.

11. A machine as specified in claim 10 and wherein are serially related means including converging guides to which the ribbon is supplied; then ribbon engaging rolls that are adjustable to afford predetermined resistance to the passage of the ribbon therethrough; then a knife for severing the ribbon; and conveyer mechanism adapted to grasp a leading end of the ribbon in the rear of the knife and pull a predetermined length of it through said guide and resistance rolls under the predetermined tension, until the desired length of ribbon is cut off by the knife.

12. A machine as specified in claim 10 having chain conveyer mechanism for conveying the ribbon material from the severing means to the compression chamber including synchronized parallel chains having adjacent lengths moving in the same direction, and ribbon grasping means consisting of fingers projecting laterally from each of the chain conveyers, in registering relation so as to cooperatively engage opposite faces of the ribbon.

13. A machine as specified in claim 10 having chain conveyer mechanism for conveying the ribbon material from the severing means to the compression chamber including synchronized parallel chains having adjacent lengths moving in the same direction, and ribbon grasping means consisting of fingers projecting laterally from each of the parallel chain conveyers, in registering relation so as to cooperatively engage opposite faces of said ribbon; each chain carrying a series of such fingers on successive links thereof, whereby the fingers individually and successively rotate out of gripping relation to the ribbon, at the exit end of the chain conveyer, thereby pushing a corresponding length thereof through the opening in the compressor chamber.

14. A machine as specified in claim 10 and wherein the spinning needles are in opposite pairs carried respectively by two aligned shafts rotating in the same direction, the respective pairs of

needles being eccentric to and parallel with the axes of said shafts; bushings rotatably mounted in the walls of the compressor, with their axes in alignment with said spinning shafts and their inner end surfaces constituting inner surfaces of the compression chamber, the pairs of spinning needles being endwise slidable in the respective bushings, and the radius of the inner rotating surfaces of said bushings being substantially greater than the radial eccentricity of said needles and means for positively retracting the needles and for spring projecting them into the leading end of the ribbon.

15. A machine as specified in claim 10 and wherein the spinning needles are in opposite pairs carried respectively by two aligned shafts rotating in the same direction, the respective pairs of needles being eccentric to and parallel with the axes of said shaft; and bushings rotatably mounted in the walls of the compressor, with their axes in alignment with said spinning shafts and their inner end surfaces constituting inner surfaces of the compression chamber, and being of a diameter approximately equal to that of the cylindrical form wound on said needles, whereby said rotating surfaces limit the length of such cylindrical form and operate as means for rotating the cylindrical form after said needles have been withdrawn; and wherein the soap discharging means is operated while the cylindrical form still has rotary motion, thereby distributing soap circumferentially of the cylinder.

16. A machine for making fluffy metal wool into relatively dense pads, including a compressor having an upright compression chamber, a piston reciprocated through the lower end thereof and a pad shaping mold at the upper end into which the piston compresses the wool, the upper end wall of said mold being a stationary plate; means for supplying the compressor with enough fluffy metal wool for a pad; and means for actuating the piston to apply high pressure to force the fluffy metal wool into the mold and form a relatively dense pad of predetermined shape; the side walls of said shaping mold being laterally slideable beneath said stationary plate to permit removal of the pad from said side walls.

17. A machine for making metal wool pads from fluffy metal wool strips of the class described, which includes traction feeding means to pull in successive lengths of strip; means for cutting off successive substantially equal lengths thereof; and a pad shaping compressor including a piston and compression chamber; said chamber having a lateral opening through which the leading end of a cut-off length of said strip is pushed endwise into the compression chamber, by the feeding means, while the piston is retracted; means for loosely winding each length to form a fluffy roll in said cylinder; said compression chamber having a pad shaping mold at its end into which the fluffy metal wool roll is highly compressed.

18. Apparatus as specified in claim 17, and in which the means for loosely winding the strip in the compressor includes a pair of spinning needles each pair endwise slideable in a rotary bushing the inner end face of which forms a portion of the side wall of the compression chamber; and means for sliding said spinning needles endwise into and out of engagement with the leading end of the strip while the piston is retracted, thereby winding it into fluffy roll.

19. A machine for making metal wool pads from fluffy metal wool strip, comprising serially related means for severing the strip into suc-

cessive lengths of approximately equal weight; a piston and a compression chamber having a pad shaping mold into which the piston compresses the wool and a lateral opening, uncovered when the piston is in the retracted position; means for pushing a predetermined length of the leading end of said strip through said opening when the piston is retracted; spinning needles and means for projecting them laterally into said leading end of the strip and winding it to form a roll; and means for discharging a measured amount of fluid soap onto the roll before it is compressed.

20. A machine as specified in claim 19, and wherein there are serially related means including converging guides to which the strip is supplied; then strip engaging guide rolls; then a knife for severing the ribbon; conveyer mechanism adapted to grasp a leading end of the strip in the rear of the knife and pull a predetermined length of it through said guide and rolls until the desired length of strip is cut off by the knife.

21. A machine as specified in claim 19, and wherein the means for pushing the end of the strip into the compressor includes synchronized parallel conveyer chains having adjacent lengths moving in the same direction, and having fingers projecting laterally from each of the conveyer chains in registering relation, so as to cooperatively grasp opposite faces of the strip.

22. A machine as specified in claim 19, and wherein the means for pushing the end of the strip into the compressor includes synchronized parallel conveyer chains having adjacent lengths moving in the same direction, and the strip grasping means consists of fingers projecting laterally from each of the parallel conveyer chains in registering relation, so as to cooperatively grasp opposite faces of said strip; and wherein each chain carries a series of such fingers on successive links thereof, whereby the fingers individually and successively rotate out of gripping relation to the strip, while pushing the leading end of the strip through the opening in the compressor chamber.

23. A machine as specified in claim 19, and wherein the spinning needles are in opposite pairs carried respectively by two aligned shafts rotating in the same direction, the respective pairs of needles being eccentric to and parallel with the axes of said shaft; bushings rotatably mounted in the walls of the compressor, with their axes in alignment with said spinning shafts and their inner end surfaces constituting inner surfaces of the compression chamber, the pairs of spinning needles being endwise slidable in the respective bushings, and the radius of the inner rotating surfaces of said bushings being substantially greater than the radial eccentricity of said needles and means for positively retracting the needles and for spring projecting them into the leading end of the strip.

24. A machine as specified in claim 19, and wherein the spinning needles are in opposite pairs carried respectively by two aligned shafts rotating in the same direction, the respective pairs of needles being eccentric to and parallel with the axes of said shafts; and bushings rotatably mounted in the walls of the compressor, with their axes in alignment with said spinning shafts and their inner end surfaces constituting inner surfaces of the compression chamber, and being of diameter approximately equal to that of the cylinder wound on said needles, whereby said rotating surfaces limit the length of such cylinder.

der and operate as means for rotating the cylinders after said needles have been withdrawn.

25. A machine for forming and cutting metal wool strip of the class described where the strips are delivered to a compressor, into lengths of approximately equal weight, including rolls for guiding the strip; synchronously driven mechanism including a knife for severing the strip; and conveyor mechanism adapted to grasp a leading end of the strip in the rear of the knife and pull it under the knife and toward the compressor until the desired length of strip is cut off by the knife.

26. A machine as specified in claim 25, and wherein the conveyor mechanism includes parallel endless members having adjacent lengths moving in the same direction, and the ribbon grasping means consists of fingers projecting laterally from each of the chain conveyers, in registering relation so as to cooperatively engage opposite faces of said strip; and wherein each chain carries a series of said fingers, on successive links thereof, whereby the fingers individually and successively rotate out of gripping relation to the strip, at the exit end of the chain conveyer, thereby pushing a corresponding length thereof beyond said exit end through an opening in the side of the compressor, above the piston and below the compression space.

27. In apparatus for making metal wool pads, a pad shaping compressor including a piston and a compression chamber in which the piston reciprocates, means operating while this piston is retracted to supply said chamber with a predetermined quantity of metal wool, said chamber having a pad shaping mold wall at the compression end thereof movable in a plane at right angles to the direction of travel of said piston, and means for moving said wall into registry with the compression chamber while a pad is being compressed therein, and means for thereafter moving it out of registry and stripping the compressed pad therefrom.

28. In apparatus for making metal wool pads, a pad shaping compressor including a piston and a compression chamber in which the piston reciprocates, means operating while the piston is retracted to supply said chamber with a predetermined quantity of metal wool in the form of a loosely wound roll, said chamber having a pad shaping mold wall at the compression end thereof laterally movable in a plane at right angles to the axis of said compression chamber, and means for moving it into registry with the compression chamber while a pad is being compressed therein, and means for moving it laterally out of registry and stripping the compressed pad therefrom.

29. In apparatus for making metal wool pads, a pad shaping compressor including a piston and a compression chamber in which the piston reciprocates; means operating while the piston is retracted to push the leading end of a strip of fluffy metal wool through a lateral opening, into said compression chamber; means for winding it to form a loosely wound roll in said chamber; a pad shaping mold wall at the compression end of said chamber; means for moving said mold wall and chamber relatively and for stripping the compressed pad from the said mold.

30. In apparatus for making metal wool pads, a pad shaping compressor including a piston and a compression chamber in which the piston reciprocates; means operating, while the piston is retracted, to push the leading end of a strip of fluffy metal wool, through a lateral opening, into

said compression chamber, and means for winding the strip to form a loosely wound roll in said chamber; said winding means including a pair of needles, each mounted eccentric to the axis of a continuously rotating shaft; and a rotatable bushing having its inner surfaces substantially flush with the inner surfaces of the compression chamber, and in which bushing said needles are endwise slidable.

31. Apparatus for making fluffy metal wool into relatively dense pads containing soap comprising, means for supplying predetermined lengths of metal wool, means for winding each length into a coil, means for injecting fluid soap into a coil of metal wool, means for rotating said coil to distribute the soap therethrough, a forming mold, means for compressing said coil of metal wool into said mold, and means for ejecting said molded material from said mold.

32. Apparatus for making fluffy metal wool into relatively dense pads containing soap comprising a compression chamber having portions of its side walls rotatable, means for supplying equal lengths of metal wool to said chamber, means for winding said lengths into said chamber forming a coil, means for injecting soap into said coil, means for rotating the said rotatable portions of said compression chamber side walls and for causing said coil to be rotated therebetween.

33. In apparatus for impregnating a mass of fibrous material with liquid, a compression chamber having a piston reciprocable within said chamber and a mold at one end of said chamber into which said piston compresses the fibrous material, the said chamber having an end wall perforated to admit liquid into said chamber, means for supplying the compressor with a mass of fibrous material, means for rotating the fibrous material within said compressor to form a cylindrical pad, means for supplying liquid through said end wall onto the fibrous material while it is rotating, and means for actuating the piston to force the fibrous material into the forming mold.

34. Apparatus for converting resilient material into pads comprising, a compressor, mold means movable in a plane at right angles to the axis of said compressor adapted to move into and out of registry with said compressor, means for pressing material from said compressor into said mold means, and means for moving said mold means to move it into and out of registry with said compressor and to transfer the formed pads from said compressor.

35. Apparatus for converting resilient material into pads comprising, a compressor, a stationary mold end wall in registry with said compressor, mold side walls movable into and out of registry with said compressor, means for pressing material from said compressor into said mold means while the side walls are in registry with the said end wall, said mold side walls being adapted to engage and transfer the formed pads from said compressor, and means for moving said mold side walls relatively to said compressor and said fixed mold end wall.

36. A machine for making fluffy metal wool into relatively dense pads, including a compressor having a piston reciprocated through one end thereof and a pad shaping mold at the other end into which the piston compresses the wool; means for supplying the compressor chamber with enough fluffy metal wool for a pad; and means for actuating the piston to apply high pressure to force the fluffy metal wool into the shaping mold

and form a relatively dense pad of predetermined shape; the said mold having side walls comprising a laterally movable frame member fitting slidably beneath the stationary end wall of the mold, and movable into and out of registry with the compressor, said frame member being one of a number of frame members each of which has a hole therein with the frame members forming a plate mounted on an axis parallel with the axis of the compressor and rotated by indexing mechanism, adapted to bring successive holes into and out of registry with the piston of the compressor.

37. A machine for making fluffy metal wool into relatively dense pads, including a compressor having a piston reciprocated through one end thereof and a pad shaping mold at the other end into which the piston compresses the wool; means for supplying the compressor chamber with

enough fluffy metal wool for a pad; and means for actuating the piston to apply high pressure to force the fluffy metal wool into the shaping mold and form a relatively dense pad of predetermined shape; said mold comprising a stationary end wall and a side wall element comprising a laterally movable frame member fitting slidably against said stationary end wall of the mold, and movable into and out of registry with the compressor, said frame member being formed as one of a plurality of similar frames equidistant from the center of a rotor turning on an axis parallel with the axis of the compressor, and rotated into and out of registry with the compression chamber, by suitable indexing mechanism.
